CLAIM

The ornamental design for a clothes storage rack, as shown and described.

DESCRIPTION

FIG. 1 is a perspective view of a clothes storage rack showing my new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof; and,

FIG. 8 is a partial enlarged view of the clothes storage rack shown in FIG. 1.

The broken lines are for the purposes of illustrating portions of the clothes storage rack and form no part of the claimed design.
